UNITED STATES PATENT OFFICE.

FREDERICK E. GREENE, OF MOUNT VERNON, NEW YORK, ASSIGNOR TO SHEPARD ART METAL COMPANY, OF DETROIT, MICHIGAN, A CORPORATION OF MICHIGAN.

DESIGN FOR INTERIOR FITTING FOR AN AUTOMOBILE BODY OR SIMILAR ARTICLE.

Application filed September 2, 1920. Serial No. 407,810. Term of patent 3½ years.

To all whom it may concern:

Be it known that I, FREDERICK E. GREENE, a citizen of the United States, residing at #116 Union Ave., Mount Vernon, in the county of Westchester and State of New York, have invented a new, original, and ornamental Design for an Interior Fitting for an Automobile Body or Similar Article, of which the following is a specification, ref-

erence being had to the accompanying drawing, forming part thereof.

The figure is a plan view of a fitting for a dome light.

I claim:

The ornamental design for an interior fitting for an automobile body or similar article, substantially as shown and described.

FREDERICK E. GREENE.
